Primary Examiner — T Chase Nelson*Assistant Examiner* — Kelly L Gross(74) *Attorney, Agent, or Firm* — Dilworth IP, LLC(57) **CLAIM**

The ornamental design for an intraoral scanner, as shown and described.

DESCRIPTION

1. Intraoral scanner

1.1 : Front

1.2 : Back

1.3 : Top

1.4 : Bottom

1.5 : Right

1.6 : Left

1.7 : Perspective view 1

1.8 : Perspective view 2

The article is a device for scanning a three-dimensional shape of an interior of an oral cavity mainly in dental treatment; the tip of the article is detachable; the article has air inlet openings and an air outlet opening in order to cool the article; the parts shown in dotted lines do not form part

(Continued)

of the claimed design; the dot-dashed lines are only to represent indeterminate length and form no part of the claimed design.

1 Claim, 8 Drawing Sheets
